UNITED STATES PATENT OFFICE.

ROBERT K. BROWN, OF WHITINSVILLE, MASSACHUSETTS.

SASH-BALANCE.

SPECIFICATION forming part of Letters Patent No. 556,659, dated March 17, 1896.

Application filed October 10, 1895. Serial No. 565,281. (No model.)

To all whom it may concern:

Be it known that I, ROBERT K. BROWN, a citizen of the United States, residing at Whitinsville, in the county of Worcester, in the State 5 of Massachusetts, have invented certain new and useful Improvements in Sash-Balances, of which the following is a specification.

My invention relates to improvements in sash-balances, such as shown in Letters Patent of the United States, granted to me December 5, 1893, No. 510,154, adapted for use in connection with window-sashes for the purpose of facilitating the raising and lowering of the window-sash, as well as preventing 10 the rattling of the sash by wind or other means, and my improvements are applicable to various kinds of window-sashes, though they are particularly applicable to sash-balances to be used on car-windows.

As is well known, the wood of which window frames and sashes are usually made is often imperfectly seasoned, and for this reason the sash and frames frequently shrink, so that they become loose and rattle in the 15 wind, and on cars they rattle both from the jarring motion of the car and from the action of the wind.

The chief objects of my invention are not only to effectively provide against the objectionable rattling of the sash and to secure 20 easy control of the window when raising or lowering the same, but also to provide a simple, economically constructed, and effective sash-balance in which the parts are compactly 25 and neatly arranged and in which the balance, when in operative position, is entirely hid from view with the exception only of the locking or unlocking lever-arm.

My objects are, further, to improve the construction of sash-balances of the character referred to, and my invention consists in the novel construction and details thereof, as 30 hereinafter described and claimed.

In the drawings, Figure 1 is a vertical section 35 elevation of part of a window-frame, showing the preferred form of my sash-balance in position. Fig. 2 is a vertical section of the sash-balance, window-frame, and window-sash shown in Fig. 1. Fig. 3 is a horizontal sectional plan view of the construction 40 shown in Fig. 1. Fig. 4 is a rear elevation of the sash-balance as illustrated in Fig.

1. Fig. 5 is a sectional detail of a modification of the spring-barrel. Fig. 6 is a modified form of the sash-engaging device. Fig. 55 7 is a horizontal sectional view of a modification hereinafter referred to.

Referring to the drawings, in which similar reference characters refer to corresponding parts in all the views, the letter A indicates the vertical stile of the window-sash, and B the vertical stile of the window-frame, against which are secured the usual retaining-strips V, between which the vertical edges of the window are held and move. 65

In Figs. 1 to 4 there is an outer casing inclosing the spring-barrel F, the latter of which in its preferred form is made of a single piece of cup-shaped metal, from the closed side of which projects the spindle P, rotatably mounted in the hub T, projecting inwardly from the inclosing-case E of the spring-barrel. The closed side of the spring-barrel is also provided with an annular projection q, fitting a corresponding recess in the projecting 70 flange D on one side of the shell or casting C, whereby the said barrel may be readily centered when the parts are assembled. The other side of the casting C is provided with a flange D' extending beyond the hub on the 75 casing E and resting against the same, as shown in Figs. 3 and 4, the two flanges thus confining between them the barrel and its inclosing-case. Two small flanges c' likewise project from the casting C on either side of 80 the flange D, for the purpose of enabling the ready application of the casting C to the window-frame, as hereinafter more fully described. This casting C, which forms the base on which the other parts are carried, is 85 made of the side walls from which the flanges D and D' project, end walls forming continuations of the side walls, and bottom plate, the latter of which is perforated or slotted to permit the sash-engaging device on the spring-barrel to project therethrough for engaging 90 the sash, as clearly seen in Figs. 1, 2, 3, and 7.

Extending from the bottom of the casting C in the same plane are two flanges c, through which suitable fastening devices, such as 100 screws, are passed into the window-frame for securing the balance in place thereon. At right angles to the bottom two guide-flanges or lips c' extend, slightly offset from the face

of the flange D, thus providing a recess in which the unlocking lever-arm L operates. These two lips are provided for the purpose of enabling the ready application of the device to the window-frame without necessitating accurate measurements, this being quickly and readily accomplished by simply setting the device, when assembled, into the recess in the window-frame with the lips aligning and flush with the box-strip in which the sash slides.

The casting C, constructed as described, forms a shallow box or shell, in which the casing E inclosing the spring-barrel is adjustably held by means of the bolts K passing loosely through holes in the bottom plate of the casting C, and through similar holes in the projecting flanges e of the casing E, the outer ends of the bolts being screw-threaded and provided with nuts n, between which nuts and flanges e coil-springs l are confined, tending to press the casing E and the spring-barrel carried thereby toward the bottom of the casting and toward the window-sash, and between the flanges e and bottom of casting C another set of coil-springs e' is confined, tending to press the casing E in the opposite direction. By screwing or unscrewing the bolts K in the nuts n, the spring-barrel may be readily, easily, and delicately adjusted with relation to the sash.

Upon the periphery of the spring-barrel F, integral therewith, I provide a spherical tooth-gear H adapted to mesh with the corresponding rack R on the window-sash, and on one edge of said barrel I also preferably provide a series of teeth h, with which teeth the locking spring-pawl S engages to hold the spring-barrel against rotation. This spring-pawl S is preferably a leaf-spring, one end of which is arranged to rest against the inner wall of the casing E, the other end being slightly bent, forming a tooth to engage the teeth h on the barrel. This spring is confined between the ends thereof by the lip G, formed by two notches on the periphery of the casing E, the body portion of the spring passing through the notches and over the outside of the lip. Within the spring-barrel is a coil-spring I, the outer end of which is confined in a recess or groove in the inner periphery of the barrel, and the other end being confined in a similar groove in the fixed hub T, so that as the window-sash is lowered the rack R engages with the spherical teeth on the barrel, whereby the latter will wind up the said spring, thus storing up energy sufficient to operate the balance in raising the window.

In order to operate the pawl S to release the spring-barrel, when it is desired to raise or lower the sash, I use a lever-arm L pivoted to one side of the axis of the barrel at v on the flange D and having one end bent so as to engage with the under side of the pawl S as the projecting end of the lever-arm is pulled downward or upward, thus unlocking

the pawl and permitting the sash to be easily raised or lowered, the energy stored up in the spring facilitating the raising and causing it to respond to the slightest pressure in raising the window. When the arm L is released, the spring-pawl instantly forces its end down and drops into engagement with the teeth h, again locking the spring-barrel. It will be observed that this lever-arm works between the two flanges c' in the casting C, the said flanges being raised above the surface of the flange D a distance equal to the thickness of the lever-arm L, thus forming a recess between the face of the flange D and the side of the recess in the window-frame. The arm L is normally out of operative engagement with the spring-pawl S, so that the pawl always locks the window against raising or lowering until the arm is operated to lift it out of contact with the teeth h on the spring-barrel, the outer or projecting arm of the unlocking-lever being provided with a suitable cord or chain, if desired, or other convenient means may be attached thereto for the purpose of operating it.

One or more of my sash-balances may be used as desired, according to the size and weight of the window, and they may be placed on opposite sides of the window-frame, the parts all being reversible and interchangeable, so that the balance may be placed on the right or left hand side of the window. When only one balance is used, it is desirable to provide a friction-roller, such as W, within a recess at the lower part of the sash, which roller overcomes any friction of the sash on the frame. While these rollers are only shown on one side, they may of course be applied to both sides, if desired.

In order to apply the sash-balance for operating the upper sash, for example, the balance, with the parts assembled as shown in the drawings, is set into the window-frame opposite the lower rail of the upper sash, so that the lower bolt K comes just below the said lower rail, in order that a screw-driver may be inserted into the slot in the bolt-head to effect the adjustment of the spring-barrel with relation to the rack on the window-sash, and the upper adjusting-bolt is adjusted in the same manner after the sash is lowered.

If it is desired to apply the balance to the lower sash, it is set in the window-frame nearly opposite the upper rail of the lower sash with the upper adjusting screw-bolt above the said rail, thus allowing the screw-driver to enter the slot in the head thereof for the purpose of adjusting the spring-barrel in the manner before stated. The sash is then raised and the other screw-bolt adjusted in the same manner.

The balance for operating a car-window sash is set into the frame near the upper rail of the sash to allow the window to be raised sufficiently high. After the sash is fitted to the frame and provided with a groove to permit the insertion of the metal strip forming

the rack in the sash without binding on the frame the strip is secured to the side of the sash, so that the centers of the teeth in the strip will center with the teeth on the spring-barrel.

In Fig. 5 I have shown a modified form of spring-barrel in which the said barrel is composed of two parts, a ring F', which is provided with the operating-teeth H in its outer

periphery, to which ring is secured a cup-shaped disk F" provided on its outer periphery with the teeth h and from the bottom of which projects the spindle P, the outer side of the disk bottom being provided with the annular projection q, as in the construction shown in Figs. 1 to 4. The two parts F' and F" are secured together by suitable screws, a rubber or other flexible washer r being confined between the meeting edges.

In Fig. 6 I have shown a common rack and pinion R' and H", which may, if desired, be used instead of the spherical tooth rack and pinion before described.

In Fig. 7 I have shown the engaging device between the spring-barrel and sash as composed of a flexible tire H," of rubber or the like, which meshes with a groove in the window-sash. In this construction the spring-barrel is preferably made of two parts x and y, the latter of which carries the teeth h and spindle P, while the former carries the hub T and is arranged to clamp the tire H" between a projecting flange thereon and a flange on the part y. These two parts are held together by screws k, a space between the parts x and y permitting of a limited adjustment of the parts with respect to each other by means of the screws k. This elastic tire will adjust itself to a limited amount of shrinkage of the window-sash, and can be further adjusted with reference to the sash by increasing or diminishing the side pressure on the tire through the medium of the screws k, a compression of the tire laterally effecting a radial expansion of the tire to take up shrinkage, and a diminution of such pressure effecting a radial contraction to compensate for swelling.

While I have shown the spring-pawl as normally disengaged with the unlocking-arm, for locking and unlocking the device, I do not wish to be confined to this specific form of mechanism, as I may adapt any suitable locking device to the various forms shown—such, for example, as the locking mechanism shown in my prior patent, No. 491,762, dated February 14, 1893.

It should be observed that to wind up the spring-barrel to the proper tension for balancing the sash the sash is put into the frame at the top and pulled down, the engaging device on the barrel meshing with the rack on the sash and causing the barrel to turn so as to wind up the spring I. Should one such operation be insufficient to secure the proper tension it may be repeated as often as necessary, taking the sash out and inserting it at the top of the frame each time.

It will be noted that the balance, after it is once adjusted and in position, is always locked, excepting only when the pressure is applied upon the unlocking-arm by the finger or otherwise to pull the operating-arm downward or upward so as to lift the pawl out of engagement with the barrel. As the pressure is removed the balance is again automatically locked.

It should be noted that the lever for operating the lower sash of ordinary windows and a railway-car sash is always within easy reach of the hand, and the pawl and lever may be reversed and interchanged for either a downward or upward movement of the arm, as the case may require; but in the case of the upper sash it is different, for when the lower sash is raised ever so little the lever on the upper balance is placed out of reach of the hand and it must be operated by a cord or chain led upward by suitable means on the frame and down to within easy reach of the hand, the movement of the lever being upward. In all windows the "parting box-strip" in frame between the two sashes makes a space between the upper rail of lower sash and upper sash-rail or the two "meeting-rails." The rails of the upper sash do not touch the upper lever-arm, and as the extreme-width line of lower meeting-rail is the center line of the parting box-strip there is a space between the lower meeting-rail and upper sash sufficient for the upper-balance lever-arm to operate in without being touched or interfered with by the lower sash-rails and the free movement of cord or chain and lever-arm to unlock upper sash-balance. This space is always equal to more than half the width of the parting box-strip in frame. Another important feature is this: For instance, where more than one balance on one sash is required, one on each side (right and left) of sash, if a locking arrangement was in operation on each side of each sash it would require two hands to operate the two unlocking-levers, and one would require a third hand to raise and lower the sash; but to obviate this only one locking device is required in operation, one on one side and the pawl and lever arranged to be inoperative on the other side, excepting only when the sash is out of frame for rewinding, for when one side is locked the other side is held effectually as if both locking devices were in operation.

I claim as my invention—

1. The herein-described sash-balance for windows, consisting of a casting or shell adapted to be secured in a recess in the window-frame, a barrel rotatively mounted in said casting, and provided with means on its periphery for engaging the side of the window-sash, a spring-pawl normally locking the barrel against rotation, and a lever-arm pivoted to one side of the axis of the barrel normally out of engagement with said pawl and arranged to lift the pawl out of engagement with the barrel, substantially as described.

2. The herein-described sash-balance for windows, consisting of a shell or casting provided with guide-lips on each end in alignment with the box-strip of the window-frame, 5 a spring-barrel rotatably mounted in the casting and having an engaging device on its periphery for engaging the side of a window-sash, with mechanism for locking and unlocking the sash-balance, substantially as described.

3. The herein-described sash-balance, consisting of a shell or casting adapted to be secured within a recess in a window-frame, a 15 spring-operated barrel, rotatably mounted in said casting, the said barrel having on its periphery an engaging device for engaging with the side of a window-sash, and a set of locking-teeth, a pawl normally in engagement with said teeth, and a lever normally out of 20 operative engagement with the pawl for lifting and holding said pawl out of contact with said teeth, to permit the barrel to rotate, substantially as described.

4. In a sash-balance, the combination with 25 the window-frame provided with a recess, of a casting or shell having flanges projecting within the recess, a spring-operated barrel rotatably and adjustably mounted between the flanges and having on its periphery a device for engaging the side of the window-sash 30 and a set of teeth for locking the barrel, a spring-pawl normally in contact with the teeth to lock said barrel, and a lever-arm pivoted to one side of the axis of the barrel upon 35 one of the flanges of the casting and adapted to raise the pawl and unlock the barrel, substantially as described.

5. In a sash-balance, the combination with the window-frame having a recess therein, of 40 a casting or shell provided with a set of flanges secured to the frame, and a pair of parallel flanges projecting at right angles thereto within the recess of the frame, a spring-operated barrel mounted in the casting 45 between said flanges, a pair of guide-lips extending from the casting so as to be quickly aligned with the box-strip of the window-

frame, the inner portions of said lips being slightly raised above the shell side and barrel-supporting flange forming a recess, a lever pivoted upon the barrel-supporting flange having one end extending through the recesses between the lips and the other end into the recess of the frame, a pawl normally locking the barrel against rotation, with which pawl the said lever-arm is adapted to engage and lift it out of contact with the barrel, substantially as described. 50

6. In a sash-balance, the combination with the shell or casting having parallel barrel-supporting flanges therein, one of said flanges being provided with a centering-recess on its inner side, an annular casing closed on one side provided with a centrally-projecting hub and adjustably mounted in the casting, a 60 cup-shaped barrel having a spindle fitting in the said hub and provided on its closed side with a circular projection meshing with the recess on the supporting-flange, substantially as described. 65

7. In a sash-balance, the combination with the shell or casting C provided with parallel flanges extending from the base thereof, an operating-barrel supported between said flanges, and projecting through the base of the shell E to engage the side of the window-sash, a cup-shaped shell inclosing the barrel, a spring-pawl having its body portion confined by notches on the periphery of the shell E and its free end normally holding the barrel against rotation, a lever pivoted on one of the flanges, one end of said lever being normally out of operative engagement with the pawl and adapted to be brought into contact therewith to disengage the pawl from the 75 barrel, substantially as described. 80

In testimony whereof I have signed my name to this specification in the presence of two subscribing witnesses.
